UNITED STATES PATENT OFFICE.

THOMAS J. HABICHT, OF CHARLOTTE, NORTH CAROLINA.

CARPET-CLEANING APPARATUS.

1,105,903.

Specification of Letters Patent.

Patented Aug. 4, 1914.

Application filed April 5, 1912, Serial No. 688,813. Renewed February 2, 1914. Serial No. 816,101.

To all whom it may concern:

Be it known that I, THOMAS J. HABICHT, a citizen of the United States, residing at Charlotte, in the county of Mecklenburg and State of North Carolina, have invented 5 a new and useful Carpet-Cleaning Apparatus, of which the following is a specification.

The present invention relates to improvements in a carpet cleaning apparatus, the primary object of the invention being the provision of an apparatus, the main compartment of which is liquid tight so as to be used to contain liquid for washing the carpet or to be used as a carpet beating and brushing compartment when cleaning the carpet, a plurality of other compartments being disposed in spaced relation thereto and connected with the main compartment by 15 means of tracks, whereby the carpet containing main roll may be moved from the first compartment to and above the other compartments to carry out the various steps in the cleaning and dyeing of the carpet. 25 With the foregoing and other objects in view which will appear as the description proceeds, the invention resides in the combination and arrangement of parts and in the details of construction hereinafter described and claimed, it being understood that changes in the precise embodiment of the invention can be made within the scope of what is claimed without departing from the spirit of the invention.

35 In the drawings—Figure 1 is a vertical longitudinal sectional view through the main compartment and vats, the elements being in the position they assume when cleaning a carpet, while dotted lines illustrate the position of the upper roll when rinsing the carpet. Fig. 2 is a section taken on line 2—2 of Fig. 1, dotted lines illustrating the position of the main roll when above one of the rinsing vats. Fig. 3 is a 45 section taken on line 3—3 of Fig. 1. Fig. 4 is a side elevation of the main vat showing the gearing for connecting the beaters and brushes for coöperation. Fig. 5 is an enlarged detail view of a portion of one of the beater rolls. Fig. 6 is a cross section through a beater roll. Figs. 7 and 8 are detail views of the upper carpet carrying roll. Figs. 9 and 10 are detail views of one of the 50 rotary brushes.

55 Referring to the drawings, the numeral 1 designates the main compartment, which is

provided with the dome 2 which has the oppositely opening covers 2', to permit access to the interior of the compartment 1.

A shaft 6 is mounted in the bearings 7', 60 which are each provided with flanged wheels 100, the purpose of which will presently appear. The roll 7 is keyed upon the shaft 6 and constitutes the main carpet receiving roll of the apparatus.

A shaft 8 is journaled transversely of the compartment 1 near the bottom thereof and carries the lower roll 9, which with the upper roll 7 provides a means for the connection of the respective ends of the carpet C 70 so that the same during the cleaning operation may assume the position as shown in Fig. 1.

In order to dry clean the carpet, a beating and brushing mechanism is disposed 75 within the compartment 1 intermediate of the respective rolls 7 and 9, and consists of the two parallel transversely disposed shafts 10 and 10', which carry the cylindrical rollers 11 and 11', respectively, each one of which 80 is provided with a plurality of spiral wires 12, which project around the circumference of the rolls 11 and 11' and provide a plurality of beaters to engage the carpet C upon opposite sides thereof, as shown in Fig. 1, 85 when passed between the beaters.

Disposed below the respective shafts 10 and 10' and in vertical alinement therewith are the shafts 13 and 13', which carry the respective rotary brushes 14 and 14', said 90 brushes being so disposed as to brush the respective sides of the carpet C during the passage thereof from the roll 7 to the roll 9 and vice versa.

In order to actuate the roller 7 to cause 95 the winding of the carpet C thereon, a crank 17 is removably connected to the end of its shaft 6 while removably keyed upon said shaft is a sprocket wheel 18 which through the medium of a crossed sprocket chain 19 100 and the sprocket 20 keyed upon the shaft 8, transmits a simultaneous motion to the lower roll 9. Thus it will be seen that the rotation of the crank 17 in one direction will cause the carpet C to be removed from the 105 roller 7 onto the roller 9, while a rotation in the opposite direction will remove the carpet from the roller 9 upon the roller 7. By this means the carpet will be moved in a downward or upward direction within the compartment 1.

In order that the respective beaters and

brushes may be actuated simultaneously during the travel of the carpet therebetween, the gears 20 are fixed upon the ends of the respective shafts 10, 10', 13 and 13' at the 5 opposite side of the machine to the crank 17 and by means of the power pulley 21, these shafts may be rotated independently of the shafts 6 and 8, so that they will be maintained at a predetermined speed, while 10 the carpet may be moved at any desired speed according to the amount of dirt carried thereby.

As is often the case in dry cleaning after the dust and dirt have been removed from 15 the carpet within the compartment 1, it is desirable to steam the carpet and when this is desired, steam is admitted through the conduit 24 into the lower part of the compartment 1, the carpet C being wound upon 20 the roller 9, or during the steaming process, the carpet may be moved to be first placed upon the roll 9 and then the roll 7 alternately, until the steam has permeated the fabric. After such steaming operation the 25 carpet is rewound upon the roller 7 and if so desired without disturbing the roller 7 the end of the carpet upon the roller 9 may be removed therefrom and carried out through the outlet controlled by the cover 2' 30 over the respective vats 23 and be spread out for drying.

What is claimed is:

1. In an apparatus of the character described, a reservoir having a dome, two superposed carpet carrying rollers journaled 35 in the reservoir, a beating mechanism and a brushing mechanism interposed between the rollers within the reservoir, a flue to remove the dust and dirt from the reservoir, said 40 dome having a hinged cover, means for re-

movably mounting the upper carrying roller for movement into and out of the dome through the portion thereof controlled by the hinged cover, and means for supporting the removable roller exterior of the reservoir. 45

2. In an apparatus of the character described, a reservoir having a dome, two superposed carpet carrying rollers journaled in the reservoir, a beating mechanism and a brushing mechanism interposed between the rollers within the reservoir, a hinged cover for one side of the dome, and means for removably mounting the upper carrying roller for movement into and out of the dome 50 through the side controlled by the cover.

3. In an apparatus of the character described, a reservoir having a dome, two superposed carpet carrying rollers journaled in the reservoir, a beating mechanism and a brushing mechanism interposed between the rollers within the reservoir, a hinged cover for one side of the dome, means for removably mounting the upper carrying roller for movement into and out of the cover controlled side of the dome, means for supporting the removable roller exterior of the reservoir, and detachable means for operably connecting the upper and lower rollers together for simultaneously operating said 60 rollers to wind the carpet from one roller to the other. 65

In testimony that I claim the foregoing as my own, I have hereto affixed my signature in the presence of two witnesses.

THOMAS J. HABICHT.
